(57) **CLAIM**

The ornamental design for a surgeon display screen with a transitional graphical user interface having staple firing icon as shown and described.

DESCRIPTION

FIG. 1 is a front view of a surgeon display screen with a transitional graphical user interface having staple firing icon in accordance with the present design;

FIG. 2 is an enlarged view of the first image;

FIG. 3 is an enlarged view of a second image;

FIG. 4 is an enlarged view of a third image;

FIG. 5 is an enlarged view of a fourth image; and,

FIG. 6 is an enlarged view of a fifth image.

The appearance of the staple firing icon sequentially transitions between the images shown in FIGS. 2-6. The process or period in which one image transitions to another image forms no part of the claimed design. The broken lines showing the display screen form no part of the claimed design. The remaining broken lines showing remaining portions of the graphical user interface form no part of the claimed design.
